UNITED STATES PATENT OFFICE.

GEORGE GUNTHER, OF LONG BEACH, AND ADELBERT J. SEBASTIAN, OF LOS ANGELES, CALIFORNIA, ASSIGNORS, BY DIRECT AND MESNE ASSIGNMENTS, TO THE GUNTHER HUMIDIFIER COMPANY, OF LOS ANGELES, CALIFORNIA, A CORPORATION OF CALIFORNIA.

DESIGN FOR A HUMIDIFIER.

Application filed January 6, 1920. Serial No. 349,816. Term of patent 3½ years.

To all whom it may concern:

Be it known that we, GEORGE GUNTHER and ADELBERT J. SEBASTIAN, citizens of the United States, residing at Long Beach and Los Angeles, respectively, in the county of Los Angeles, State of California, have invented a new, original, and ornamental Design for Humidifiers, of which the following is a specification, reference being had to the accompanying drawing, forming part thereof.

The figure is a perspective view of a humidifier, showing my new design.

Our humidifier is intended primarily for use in connection with internal combustion engines, being most commonly used on automobiles, where it is usually mounted on the dash board.

We claim:

The ornamental design for a humidifier, as shown.

GEORGE GUNTHER.
A. J. SEBASTIAN.
